UNITED STATES PATENT OFFICE.

DAVID J. SMITH, OF LONDON, ENGLAND.

SCRUBBER, CLEANSER, AND COOLER FOR GAS.

1,307,321.

Specification of Letters Patent. Patented June 17, 1919.

Application filed November 29, 1918. Serial No. 264,713.

To all whom it may concern:

Be it known that I, DAVID JOSEPH SMITH, major in the Army Service Corps, a subject of the King of Great Britain and Ireland, 5 and a resident of 40 Woodberry Grove, Finsbury Park, London, N. 4, England, have invented new and useful Improvements in Scrubbers, Cleansers, and Coolers for Gas, of which the following is the specification.

10 This invention relates to devices used to cool, cleanse or scrub gases, and particularly to such devices used in connection with gas producers either suction or pressure operated, the gases being thus either drawn or forced through the scrubber.

15 The objects of this invention are (1) to reduce the size and weight of the scrubber; (2) to reduce the resistance by friction or back pressure on the gases passing through 20 the scrubber, and (3) to render the apparatus suitable among other purposes for use on motor vehicles propelled by internal combustion engines operated by suction gas.

25 In the preferred form of construction the scrubber consists of a vertical cylinder of any suitable material and size, having fitted therein a smaller cylinder which is secured at the bottom of the larger cylinder concentrically, and projects upwardly nearly to 30 the top cover thereof. The annular space between the two cylinders is fitted with ring disks of suitable material preferably sheet metal forming interrupted paths extending to within a suitable distance from the bottom 35 tom of the main cylinder. The gas is caused to enter from the producer at the side of the main cylinder and to pass up the said interrupted paths. Water fed by a pump flows into the top of the main cylinder and runs 40 down the said paths meeting the ascending gas on its way, and the latter is cooled and washed thereby. The water passes to the bottom of the main cylinder and leaves the scrubber preferably by the same pipe by 45 which the gas enters. The gas on reaching the top of the main cylinder passes down the smaller inner concentric cylinder. This cylinder is filled nearly to the top with pieces of coke or other suitable material 50 through which the gas is caused to pass. Suitable means are provided to prevent any portions of coke, etc., which may become detached from being drawn into the gas outlet pipe, and provision is made for draining 55 both the larger and smaller cylinders when necessary. The coke or the like is

held in a wire or other suitable basket, so that it can be withdrawn by taking the cover off the main cylinder for cleaning or removal. By this means the quantity of coke 60 or cleaning material is reduced to a minimum and the gas leaves the scrubber much drier than when passed through a scrubber of the ordinary design, and there is much less frictional resistance to the flow of the 65 gas. The pump or water supply to the scrubber is arranged to be controlled either by the engine using the gas or by the fan forcing gas through the scrubber, so that the water supply is mechanically controlled 70 and in proportion to the quantity of gas passing through the scrubber.

By the construction described herein, the size of the scrubber as also the weight, can be reduced to a minimum which renders the 75 scrubber suitable for use on automobiles, or for other vehicle purposes where the working conditions are liable to fluctuate rapidly.

And in order that my invention may be completely understood, reference should be 80 made to the accompanying sheet of drawings which illustrates the preferred mode of carrying it into effect.

Figure 1 is a sectional elevation of the apparatus.

Fig. 2 is a detail plan view of one of the ring disks.

Fig. 3 is an edge view of same.

Fig. 4 is a section of the slot in the disk on the line Z of Fig. 2.

Fig. 5 is an elevation of the wire basket for holding the coke.

Fig. 6 is a plan of same.

Fig. 7 is a sectional view of three of the ring disks and their spacing rings, showing 95 the arrangement of the disks with respect to one another.

Fig. 8 is a section on the line 8-8 of Fig. 1.

Referring to Fig. 1, A is the outer or 100 main cylinder and B is the inner concentrically arranged cylinder. The cylinder A is fitted with closing or cover plates A¹ A² secured at the top and bottom of the cylinder respectively by means of bolts passed 105 through flanges A³ A⁴ brazed or welded to the said cylinder or integrally formed therewith. The cylinder B is mounted upon and carried by the lower cover plate A², the cylinder projecting below same. The 110 cylinder is closed at its lower end by the cover plate B¹ which has fitted therein a

drain cock B², for the removal of deposit or sludge.

An annular angle flange A⁵ is rigidly secured on the inside of the cylinder A and 5 a corresponding annular angle flange B³ is secured on the exterior of the cylinder B. The flanges A⁵ B³ serve as supports for the series of disks as shown in Fig. 1, one of which is shown in plan and edge view respectively in Figs. 2 and 3. Each ring disk C is of thin sheet metal loosely fitting as to its exterior edge C¹ the interior of the cylinder A and as to its inner edge C² the exterior of the cylinder B. Each disk C is 10 formed with a slot C³ cut through it having one lateral edge of same C⁴ turned upwardly and the other C⁵ downwardly, see section on line Z shown in Fig. 4. The ring disks C are arranged in a superposed manner in 15 20 25 30 35 40 45 50 55 60 65 70 75 80 85 90 95 100 105 110 115 120 125 130

the annular space or chamber D between the cylinders A and B. Each disk C is spaced apart from the next by suitable means such as the rubber rings E, F, the rubber ring E of smaller diameter fitting against the exterior wall of the cylinder B, and the rubber ring F of larger diameter fitting next the inner wall of the outer cylinder. Each rubber ring F is held outwardly against the cylinder wall by the outer ends of the lips C¹ C² which are cut from the disk as shown in the plan, Fig. 2, in forming the slot C³, the lips being turned up at right angles as shown in Fig. 3. The ring is also held at 90 degrees from the slot by the lips G, G, which are formed by cutting slots on the edges of each ring disk. A third lip G is formed diametrically opposite the slot C³. The slot C³ is provided to permit of the passage of the water through the ring disk C to the next ring disk beneath it. Each such slot C³ is placed diametrically opposite in position to the said slots in the adjacent disks immediately above and below it, see Fig. 7. As a result of this arrangement the water delivered to the scrubber by a pump not shown is conveyed by the pipe K to the annular chamber L and trickles downwardly through the slot C³ in the top disk C to the next disk and around the two semi-circular passages thus provided to the slot C³ on the disk below, and so on through all the successive passages between the superposed disks as shown which are spaced apart by the rubber rings E, F. The pipe K is bent round in ring formation as indicated and is provided with perforations K¹ on its lower surface through which the water trickles.

The pump is preferably mounted on the 60 gas producer afterward referred to, to which the apparatus described herein is an accessory.

The gases to be cleaned are delivered 65 from the producer by the pipe M to the annular chamber D whence they pass by the

slot C³ in the lowest disk by the two semi-circular passages provided between that disk and the next above it before referred to, to the opposite slot C³ in the next disk, and so on through all the said passages 70 provided between each pair of disks in succession until the gases reach the annular chamber L at the top. Meanwhile the water delivered through the perforations K¹ in the annular delivery pipe K travels by 75 gravity downwardly through the same semi-circular passages thus provided in succession until the water reaches the annular chamber D, thence the water passes from the scrubber by the same pipe M as the 80 gases enter thereto. The gases in their upward passage are thus exposed to the continuous downwardly moving stream of water.

The gases on delivery to the chamber L 85 pass beneath the edge of the cone L¹ and into the interior of the cylinder B. The interior of this cylinder is packed with pieces of coke which are retained or held in position by the wire basket N which is 90 shown separately in elevation and plan respectively in Figs. 5 and 6. Hooks N¹ are provided at the top of the wire basket or cage for placing in position over the upper edge of the inner cylinder B. On passing 95 from the coke chamber the gases are deflected outwardly by the conical deflector O¹ in the chamber O, and then conveyed to the internal combustion engine to be supplied by the pipe O². The conical deflector 100 O¹ serves to separate solid particles from the gases and to deposit same in the chamber O before the gases enter the pipe O².

Tarry refuse or sludge is removed from the chamber D by the plug D¹ or from the 105 chamber O by the cock B².

In employing the scrubber described with a gas producer supplying an internal combustion engine the water supply by the pump may be controlled, it will be understood, by the engine making use of the gas supply in any suitable manner.

What I do claim as my invention and desire to secure by Letters Patent is:—

1. An apparatus of the character described, comprising two concentrically and vertically arranged cylinders forming inner and outer chambers communicating with each other at the top, a filtering medium in one of these chambers, means in the other 115 chamber for forming a circuitous passage therethrough, means for delivering water in the form of a spray to the upper portion of the chamber having the circuitous passage, means for delivering the gas to the lower 120 portion of the said chamber, and means for conveying the purified gas from the chamber containing the filtering means.

2. An apparatus of the character described comprising two concentrically and 125

- vertically arranged cylinders forming inner and outer chambers communicating with each other at the top, a filtering medium in the inner chamber, a plurality of disks centrally apertured to receive the inner cylinder and supported in the outer chamber one above the other, each disk being provided with an opening and the disks being arranged so that the openings of adjacent 5 disks will be at opposite sides, means for delivering water in the form of spray into the outer chamber at the top thereof, and means for delivering the gas at the lower portion of the said chamber.
- 10 15 20 25 30 35 40 45 50
- 15 3. An apparatus of the character described, comprising two concentrically and vertically arranged cylinders forming inner and outer chambers communicating with each other at the top, the inner cylinder extending through the bottom of the outer cylinder, a plurality of disks centrally apertured to receive the inner cylinder and arranged in the outer chamber one above the other intermediate of its ends, each disk being provided with a slot and arranged so that the slots of adjacent disks will be at opposite sides, means for supporting a filtering medium in the inner chamber above the lower end thereof, a water spraying pipe for delivering water into the outer chamber, a gas delivery pipe for delivering the gas into the outer chamber below the disks thereof, and an outlet pipe leading from the lower projecting end of the inner cylinder.
4. An apparatus of the character described, comprising two concentrically and vertically arranged cylinders forming inner and outer chambers communicating with each other at the top, the inner cylinder extending through the bottom of the outer cylinder, a plurality of disks centrally apertured to receive the inner cylinder and arranged in the outer chamber one above the other intermediate of its ends, each disk having a slot and arranged so that the slots of adjacent disks will be at opposite sides, a coke carrying basket supported in the inner chamber, a cone above the said inner chamber, a water spraying pipe for delivering water to the outer chamber, a delivery pipe for delivering gas to the outer chamber below the disks, a cone supported in the inner chamber below the outer chamber, and an outlet pipe for the gas leading from the projecting end of the inner cylinder.

DAVID J. SMITH.
